UNITED STATES PATENT OFFICE.

JOHN EDGAR HIRES, OF LANGHORNE, PENNSYLVANIA, ASSIGNOR TO JOSEPH P. KERRIGAN, OF PHILADELPHIA, PENNSYLVANIA.

GAS RANGE.

Application filed September 13, 1922. Serial No. 587,875.

To all whom it may concern:

Be it known that I, JOHN EDGAR HIRES, a citizen of the United States, and a resident of Langhorne, in the county of Bucks, 5 State of Pennsylvania, have invented certain new and useful Improvements in Gas Ranges, of which the following is a specification, reference being had to the accompanying drawings.

10 A principal object of my invention is to provide a gas range suitable for domestic purposes and embodying means whereby cooking may be accomplished on the top of the range in the ordinary manner, an oven suitable for baking, and a chamber, which for convenience I designate the broiler chamber, intended for broiling or other culinary operations in which it is desired to subject the article being cooked 15 to the direct, or substantially direct, action of the flames from the burners, and to so design and correlate the various instrumentalities employed as to facilitate the utilization of the range in the performance 20 of various culinary functions with a minimum expenditure of fuel.

Further objects of my invention are the provision in a range embodying the foregoing characteristics, of a plurality of 25 burners adapted to be so positioned that the heat therefrom may be respectively directed either upwardly or downwardly as may be desired thereby facilitating the use 30 of the range in the operations of cooking 35 on the top thereof or of broiling in the compartment primarily intended for that purpose.

A further object is the provision of 40 means in the preferred embodiment of the invention whereby the products of combustion generated by the burners may be caused to pass directly into the smoke pipe or in the alternative directed about and into the oven and from thence into the smoke pipe, 45 as well as an auxiliary burner so positioned with respect to the main burners and to the oven as to supplement the heat generated by the main burners when desired so as to permit the oven to be raised to a required 50 temperature in a very short period of time, the said auxiliary burner being further adapted to thereafter maintain the desired oven temperature without material recourse to the main burners.

55 A still further object of my invention is

to provide a passage for the travel of the products of combustion free from "pockets" or by-passages which I have found cause marked decrease in the temperature, and consequent loss of efficiency.

The invention further contemplates a novel method of directing the course of travel of the air requisite to support combustion with respect to the burners of the range including the arrangement of the 60 ports for the admission of the air in such manner that after the air is drawn therethrough it will pass through one of the main burners and thence over and adjacent another of the burners where the air and 65 products of combustion generated at the first burner are raised to a still higher temperature, thence passing over the auxiliary burner and into the oven thereby insuring, with a minimum expenditure of gas, the 70 raising of the products of combustion to a high temperature before passing to or about the oven.

The foregoing as well as various other 75 objects and novel features of construction 80 and arrangement comprehended by my invention will be more fully apparent from the following description of a preferred embodiment of the invention taken in connection with the drawings forming a part 85 hereof.

In the said drawings in which, as hitherto 90 stated, is shown a preferred embodiment of my invention, Figure 1 is a vertical longitudinal section of the range substantially 95 on line 1—1 in Fig. 2, certain parts, for convenience of illustration, being shown in elevation. Fig. 2 is a transverse vertical section on line 2—2 of Fig. 1; and Fig. 3 a similar section on line 3—3 thereof. Fig. 4 95 is a top plan view of one of the main burners removed from the range; Fig. 5 a section thereof on line 5—5 in Fig. 4; and Fig. 6 a front elevation thereof. Like numerals are used to designate the same 100 parts in the several figures.

As shown, the range comprises a rectangular base 1 either adapted to rest directly on the floor in the manner illustrated or to be supported on suitable feet or 105 legs. To this base is suitably secured a rear wall 2 and end walls 3 and 4 formed of sheet metal, the walls 2 and 3 terminating at a suitable height to support the horizontally disposed range top 6, preferably 110

formed of cast iron, and conveniently provided with a plurality of symmetrically disposed, laterally spaced holes 7 and 8, positioned toward the front of the top and 5 adapted to be closed with suitable stove lids in the ordinary manner. If desired the top may also be provided with corresponding holes positioned more nearly adjacent the rear thereof, one of which is shown in Fig. 10 2, at 8', and with an extension or shelf 9 removably secured thereto.

The wall 4 is continued upwardly beyond the top 6 for a suitable distance to extend above the baking oven, generally designated 15 as 10, and is joined to the top wall 12 which extends horizontally over the chamber in which the oven is disposed and, in turn, is joined to a vertically extending wall 13 which forms the opposite side of the oven 20 chamber and terminates at the right hand end of the top 6 when viewed as in Fig. 1. It will thus be observed that in the form of the invention illustrated, the range top is disposed at the left hand end of the range 25 when viewed as in Fig. 1, and that the oven, hereinafter more particularly described, is located in a suitable chamber at the right hand end of the range and above the plane of the top, but it will of course be readily understood that the relative positions of the oven and the top may be reversed so that the former will be disposed at the left hand end of the range and the latter at the right hand. 30

35 Beneath the range top and adjacent the front of the range is arranged the broiler chamber, generally designated as 15, the said chamber being bounded by a bottom 16, rear wall 17, and ends 18, which latter, 40 together with the rear wall, extend upwardly from the bottom, which may be disposed at any suitable height, to terminate at the horizontally disposed burner plate 20. This plate, conveniently formed of cast 45 iron, is disposed at a suitable distance below the top 6 and arranged to extend from the end wall 3 to substantially the plane of the wall 13 and entirely across the upper end of the broiler chamber so that in effect 50 it forms a top therefor. This plate is further provided with laterally spaced, preferably circular burner openings respectively arranged beneath the holes 7 and 8, and adapted for the reception of the main burners, hereinafter more particularly described. 55 If desired a lining plate 17' may be disposed adjacent the rear wall 17 of the broiler chamber and forwardly spaced therefrom thereby providing a dead air space forming a heat 60 insulator at the rear of the broiler chamber, while from the upper edge of the wall 17, a plate 23 is extended rearwardly and preferably slightly angularly upward to meet the rear wall 2 of the body of the range 65 thereby cutting off the space in the rear

of the broiler chamber from the space beneath the rear part of the top as clearly shown in Fig. 2. I have found that by disposing the plate 23 with a definite inclination from front to rear, a considerably 70 greater temperature is imparted to the superposed portion of the top and a more even and efficient circulation of the heated air and products of combustion in their passage from the main burners to the flue 53, 75 hereinafter described, is effected than if the said plate is horizontally disposed. If desired a plate 23' may be secured to the under side of plate 23 and spaced therefrom in parallel relation therewith so as to provide a dead air space and minimize heat radiation through the plate 23 into the space behind the broiler. 80

The front of the stove beneath the broiler oven is provided with a transversely extending plate 24 to which is hinged, as at 85 25, a suitable door 26 through which access may be had to the broiler oven, this door being arranged to close against a plate 28 extending from the upper edge of the door 90 to the underside of the top 6 and for substantially the length of the latter, while the spaces between these plates at the ends of the broiler oven are also permanently closed by suitable vertically extending 95 plates, not shown.

The main oven 10 hitherto referred to, 100 comprises a preferably substantially rectangular box or casing, open at its front side and having a bottom 32, end walls 33 and 34, a top 35 and a rear wall 36, the size of the oven being such that when disposed in the chamber formed for its reception in the upper part of the range, it is spaced from the walls of that chamber so as to 105 leave spaces 37 and 38 adjacent the end walls of the oven, a space 39 adjacent its top wall and a space 40 adjacent its rear wall. The functions of certain of these spaces will hereinafter more fully appear. 110 In the form of the invention shown, the chamber in which the oven is disposed is provided with double outer walls, formed by placing a lining plate or wall 2' adjacent and inwardly spaced from the rear wall 2, and similar plates 4', 12' and 13' 115 respectively adjacent and inwardly spaced from the walls 4, 12 and 13, thus providing heat insulating air spaces at the ends, back and top of the oven chamber. 120

The top 35 of the oven proper is extended laterally beyond the ends of the oven to meet the lining walls 4', 13' and thus close the upper ends of the spaces 37 and 38, while the rear wall 36 of the oven, 125 is carried upwardly to meet the lining wall 12', as clearly shown in Fig. 3. The front or open end of the oven is provided with a door 42, conveniently hinged at 43, while a suitable plate or plates, generally design- 130

nated as 45, are arranged to permanently close the front of the spaces between the edges of the door and the walls of the range proper.

- 5 The chamber in which the oven is positioned is provided with a bottom plate 50 conveniently arranged in prolongation of the burner plate 20 and in the space beneath this plate and above the base may be arranged a plurality of shelves 51 and 52 convenient for the reception of dishes and other articles. In order to provide a flue 53 for the conduct of the products of combustion from the space between the burner 10 plate and the range top, an upwardly inclined flue plate 54 is arranged above the plate 50 to extend from a point adjacent the burner plate 20 to the lining plate 4', the width of this flue plate from front to back being conveniently substantially equal to the depth of the oven and its inclination such that its point of contact with the lining plate 4' is substantially in the plane of the bottom of the oven. A vertical partition, 56, is arranged adjacent the rear end of the flue plate, while a horizontal partition 57 is disposed in the rear of the wall 36 at the bottom of the space or flue 40 so as to completely close the same. It is to be noted 15 I have found that an inclined disposition of the flue plate 54 is of marked advantage in effecting a free and even flow of the heated air and products of combustion and in avoiding the setting up of eddy currents 20 and "dead gas" spaces with consequent effects inimical to maximum heating efficiency.

It will be understood that certain of the walls and partitions heretofore described 25 are provided with suitable ports to permit the passage of air to the burners and the products of combustion from the burners and the arrangement and location of these ports will now be described. For admitting 30 air for the purpose of supporting combustion, the wall 3 and the wall 18, are provided with a plurality of ports 60 of suitable size, through which air from the exterior of the range can pass into the broiler 35 chamber and from thence up through one of the main burners, hereinafter more particularly described, and along the space between the top 6 and the burner plate. Upon leaving this space as indicated by the arrows, the products of combustion pass into 40 the flue 53 formed between the bottom of the oven and the flue plate 54 and would thence, in the absence of any deflecting means, find their way upwardly, for the 45 most part, through the space or flue 37, thence through ports 62 provided in the extended portions of the top plate 35 of the oven, thence through an elongated port 63 in the upper part of the rear 50 wall of the oven and into the smoke pipe, generally designated as 65, which is arranged to communicate with the space 40 at the rear of the oven. In the preferred embodiment of the invention, however, in order to control the movement of the products of combustion and deflect them in such manner as will cause them to pass about and through the oven when desired, I may provide a damper 70, horizontally disposed and extending from front to back 55 in the space 37. This damper is controlled through the medium of a handle 71 from the exterior of the range in such manner that it may be turned to a position, as shown in Fig. 1 in full lines, in which it will cut off the passage of the gases to the upper part of the space 37 and deflect a portion of them into the oven through vertically spaced rows of ports 73 formed adjacent the lower part of the end wall 33, while under such conditions another part 60 of the gases will pass through the flue 53 above the flue plate 54 and thence through corresponding rows of ports 74 in the wall 34 into the oven from the opposite side, a permanent deflector 75 being arranged above the ports 74 so as to prevent these gases passing upwardly into the upper part of the space 38. As the rear wall 36 of the oven is provided near its upper extremity 65 with a row of ports 77 giving access to the upper part of the flue 40 and the top wall of the oven with other ports 78 giving access to the space 39, the heated gases which enter the oven through ports 73 and 74 are enabled to find their way into the smoke pipe 65, either through the ports 77 or the ports 78 and 63, as will be readily apparent from the course of the arrows in the drawing. Preferably, there are disposed upon the plate 35 and inclined upwardly and inwardly in the space 39, a plurality of deflecting plates 80 which to some extent assist in properly directing the course of the gases to the smoke pipe.

It will, of course, be understood that the main oven and broiler oven are preferably provided with suitable brackets 81 secured to their end walls to afford support for shelves in the usual manner and that if desired the stove top 6 may be enclosed or partially enclosed by a hood or canopy generally designated as 85, detailed description of which, however, is deemed unnecessary.

The range is provided with a plurality 120 of suitable burners, comprising main burners and an auxiliary burner, the former preferably being made reversible, so that the heat therefrom may be directed downwardly into the broiler chamber or upwardly 125 toward the top 6 at will. More particularly referring to Figs. 4 to 6 inclusive in which a preferred form of burner 90 intended for use in the opening in the burner plate more nearly adjacent the oven is illustrated, the 130

same comprises substantially an annular closed body 91 provided in its upper space with a plurality of radiating series of jets 92, and with a duct 93 leading to the interior 5 of the body and through which the gas passes to the jets. The burner is enlarged in the vicinity of the outer end of the duct as at 94 to provide a cylindrical boss which, when the burner is in position, extends 10 through the plate 28, the outer end of the duct being partially closed by the ported air regulating plate 95, held in adjusted position by a set screw 96. Through the center of the plate is extended one end of 15 the gas control cock 97, the other end of which communicates with a manifold 98 extending across the front of the range and connected with a suitable source of gas supply. The burner is also provided at a position 20 diametrically opposite the boss 94 with an arm 99, terminating in a cylindrical boss 100 which, when the burner is in position, is adapted to extend through suitable apertures in the plates 17 and 17' to 25 afford support to the burner at that point. For effecting the inversion of the burner the boss 94 may be provided with a conveniently positioned handle 101 while a lug 102 is so arranged as to contact with a suitably positioned stop member or members so 30 as to hold the burner either in upright position, as shown in the drawings, or in inverted position so as to direct the heat downwardly into the broiler chamber. The 35 diameter of the body of the burner is preferably such as to permit the burner to fit quite snugly in the aperture designed for its reception in the burner plate so that little or no air is enabled to pass adjacent 40 this burner from the broiler chamber to the space above the burner plate when the burner is in upright position.

The burner 90' employed adjacent the ports 60, however, is arranged in such manner that the air drawn into the said ports 45 may readily pass through the burner and into the space above the burner plate and to this end the webs between the radiating series of jets are cut away in the ordinary 50 manner so as to provide a spider-like burner which in all other respects is, however, substantially similar to the burner 90 hitherto described. It will thus be observed when this burner 90' is in upright position, air 55 from the ports 60 may readily pass therethrough and thence over the burner 90 which latter burner tends to raise the temperature of the pre-heated gases and products of combustion to a considerably greater degree 60 before they pass to the vicinity of the oven.

I also prefer to provide an auxiliary burner 105 conveniently comprising a horizontally positioned, transversely extending pipe having a plurality of jets 106, arranged 65 substantially at the large end of the flue

53 in such position that when lighted it is effective to additionally heat the gases and products of combustion from the main burners as they pass into the flue. This burner is fed from the manifold 98 and controlled through the medium of a valve 107 in the usual manner. It is found in practice, that by the utilization of this burner in conjunction with the main burners, the oven may be very rapidly brought to a baking temperature and that thereafter, one or both of the main burners may be shut off and the oven maintained at a sufficiently high temperature for most culinary operations by the use of the auxiliary 75 burner alone.

It will be noted that in a range of this character utensils may be disposed on the top 6, either directly over the burners or more in the rear thereof for slower cooking 85 and that unless the lids are removed the utensils are not exposed to the direct action of the burner flames, while all of the air necessary to support combustion is drawn through a single row of ports and when the burners are in upright position passed through one of them and then additionally heated by another and if desired by the auxiliary burner before reaching the vicinity of the oven, the damper 70 assisting in directing the hot gases either through the oven and thence into the smoke pipe or more directly into the latter should it be desired, while by effecting an inversion of one or both of the main burners, the flames therefrom may be directed downwardly toward any article disposed in the broiler oven for the purpose of broiling the same the heat thence passing upwardly and into the 95 flue 53.

It has also been found in practice that the method of heating the air and gases by passing the same through one burner and then over another, and then employing these highly heated gases and products of combustion in and about the oven results in a large saving of fuel and an entirely satisfactory operation of the oven, while by the use of the auxiliary burner positioned so as to additionally heat all of the gases before 110 they reach the vicinity of the oven, the temperature of the latter may be very quickly brought to the requisite degree and thereafter maintained with one or more of the main burners entirely closed off.

While I have herein described and illustrated with particularity a preferred embodiment of my invention, it will be understood that the same is capable of numerous modifications in construction, design and arrangement of parts and I therefore do not thereby desire or intend to limit myself specifically to the precise form of the invention so illustrated and described, as suitable modifications and changes may be made therein if 125 130

desired without departing from the spirit and scope of the invention as defined in the appended claims.

Having thus described my invention, what

5 I claim and desire to protect by Letters Patent, is:

1. A gas range comprising a top, a burner plate disposed beneath and spaced from said top, a plurality of invertible burners adjacent said plate, a broiler oven beneath the burners, a baking oven disposed above and at one side of said top, a flue beneath said baking oven communicating with the space between the burner plate and the top, an auxiliary burner disposed substantially at the junction of said flue and said space, and means beneath said burner plate and in the wall of said broiler oven adapted to admit air to said oven to support combustion in 20 said burners.

2. A gas range comprising a top, an apertured burner plate disposed beneath and spaced from said top, a broiler oven positioned beneath said burner plate, main burners disposed adjacent the apertures in said plate, only one of said burners being adapted to permit the passage of a substantial volume of air therethrough, a broiler oven disposed beneath said burners, ports in the wall of 30 said oven for admitting air thereto and thence through said burner, a baking oven disposed above and at one side of said top, and a flue extending beneath said oven and communicating with the space between said top and said burner plate.

3. A gas range comprising a top, an apertured burner plate beneath the top, a plurality of main burners disposed adjacent the apertures in said plate, one of said burners being adapted to permit the passage of a substantial volume of air therethrough and another of said burners being substantially closed against the passage of air, means beneath said burners adapted to admit air from the exterior of the range to support combustion at said burners, a baking oven disposed above and at one side of said top, a flue beneath said baking oven communicating with the space between said top and said burner plate, and means in the walls of 45 said baking oven adapted to permit the entrance from said flue of the heated air and the products of combustion generated at said burners.

4. A gas range comprising a top, an apertured burner plate beneath said top, a pair of burners respectively disposed adjacent said apertures, one of said burners being adapted to permit the passage therethrough of a substantial volume of air and the other burner being substantially closed against the passage of air, means adjacent and beneath the first-mentioned burner for permitting passage of air from the exterior 55 of the range to said burner, a baking oven

positioned above, at one side of and adjacent the second-mentioned burner, a flue beneath said oven communicating with the space between the top and the burner plate, and means in the walls of said oven adapted to permit the entrance thereto of products of combustion and heated gases passing from said burners into said flue.

5. A gas range comprising a top, an apertured burned plate positioned beneath said top, a plurality of main burners arranged adjacent said apertures, one of said burners being adapted to permit the passage of a substantial volume of air therethrough, and the other burner being substantially closed against the passage of a substantial volume of air therethrough, means beneath said first-mentioned burner adapted to admit air thereto, an oven disposed above and to one side of the second-mentioned burner, a flue extending from the space between the burner plate and the top to said oven, and an auxiliary burner disposed substantially at the end of the flue adjacent the main burners.

6. A gas range comprising a top, an apertured burner plate disposed beneath the top, a plurality of invertible main burners arranged adjacent said apertures, a broiler oven beneath said burners, means for admitting air through the wall of said oven to support combustion in said burners, a baking oven disposed above and at one side of said burners, a flue extending from the space between the top and said burner plate to said oven, and an auxiliary burner disposed in said flue substantially at the end thereof adjacent the main burners.

7. A gas range comprising a top, an apertured burner plate disposed beneath the top, main burners arranged adjacent said apertures and adapted for inversion, means for admitting air through one of said burners and in the space between the top and the plate to support combustion at both of said burners, an oven chamber disposed above and to one side of said burners, an oven disposed in said chamber and spaced from the walls thereof, a smoke pipe communicating with said chamber, a flue beneath said oven and communicating with the space between the top and the burner plate, a plurality of ports in the oven wall, and means for directing the gases and products of combustion either directly from said flue to said smoke pipe or through the ports in the walls of said oven.

8. A gas range comprising a top, an apertured burner plate spaced beneath said top, invertible burners disposed adjacent said apertures, a broiler oven beneath said burners, means in the wall of said oven for admitting air to one burner for supporting combustion at both burners, an oven chamber above and at one side of said burners,

- an oven disposed in said chamber and spaced from the walls thereof, a plurality of ports in the lower part of the walls of said oven, a flue communicating with said ports and with the space between the top and the burner plate, a smoke pipe at the upper part of said oven chamber, and means in said chamber operative to direct the gases and products of combustion generated in said burners either through said ports into the oven or directly to said smoke pipe through the space surrounding said oven.
9. A gas range comprising a top, an apertured burner plate spaced beneath said top, invertible burners disposed adjacent said apertures, a broiler oven beneath said burners, means in the wall of said oven for admitting air to one burner for supporting combustion at both burners, an oven chamber above and at one side of said burners, an oven disposed in said chamber and spaced from the walls thereof, a plurality of ports in the lower part of the walls of said oven, a flue communicating with said ports and with the space between the top and the burner plate, an auxiliary burner disposed in said flue, a smoke pipe at the upper part of said oven chamber, and means in said chamber operative to direct the gases and products of combustion generated in said burners either through said ports into the oven or directly to said smoke pipe through the space surrounding said oven.
10. In a gas range, the combination of a top, an apertured burner plate disposed beneath and spaced from said top, a burner disposed adjacent each aperture in said plate, one of said burners being arranged to prevent the passage of a substantial volume of air therethrough and another of said burners being arranged to permit the passage therethrough of a substantial volume of air, a broiler oven beneath said burners and means in the walls of said oven for admitting air thereto to support combustion at both of said burners.
11. In a gas range, the combination of a top, an apertured burner plate spaced below said top, a burner substantially closing one of said apertures, a burner only partially closing another of said apertures, a closed chamber beneath said burners, and means in the wall of said chamber for admitting air to support combustion at both of said burners.
12. In a gas range, the combination of a top, an apertured burner plate spaced below said top, a burner arranged adjacent each aperture in the plate, one of said burners being arranged to permit the upward passage of air therethrough in a substantial volume and another of said burners being closed against the passage of a substantial volume of air therethrough, a closed chamber beneath said burners; and means in the wall of said chamber for admitting air thereto whereby in the operation of the range the air passing from said chamber through said first-mentioned burner is raised in temperature and thereafter, passing through the space between the top and the burner plate, is additionally heated at said second burner.
13. A gas range having end walls, a rear wall, a top adjacent one of the end walls, an oven spaced above the top and adjacent the other end wall, a burner plate spaced beneath said top, an inclined plate extending from the rear edge of the burner plate to the rear wall of the range beneath said top, and a flue having an upwardly inclined bottom extending from the space between the top and the burner plate to the oven.
14. A gas range having end walls and a rear wall, a top adjacent one of the end walls and extending to the rear wall, an oven above the top and adjacent the other end wall, a horizontally disposed burner plate spaced beneath the top, and upwardly inclined plate extending from the rear edge of the burner plate to the rear wall of the range and spaced beneath the top, and an upwardly inclined flue plate extending from a side edge of the burner plate to the side wall of the range adjacent the oven and forming the bottom of a flue extending beneath the oven.
15. The method of supplying air to support combustion at the burners of a gas range employing a plurality of burners which consists in conducting the air for all the burners through a common inlet, thence over one of the burners and thence over the other burners in succession whereby the same air is successively heated by the several burners.
16. The method of supplying air to support combustion at the burners of a gas range employing a plurality of burners which comprises the steps of causing the air to be drawn through a common inlet and thence successively passed over the several burners toward a common outlet whereby the air is progressively heated by the different burners.
17. The method of supplying air to support combustion at the different burners of a gas range which includes the steps of admitting the air through a common inlet, causing the air to pass upwardly through one of the burners and thence progressively over the other burners to a common outlet whereby the air is progressively raised in temperature by the several burners in its passage thereover.
- In witness whereof, I have hereunto set my hand this 11th day of September, 1922.
- JOHN EDGAR HIRES.
